Primary Examiner—Melody N. Brown
Attorney, Agent, or Firm—Jefferson Perkins

[57] **CLAIM**

The ornamental design for a bicycle shifter grip with sharktooth design, as shown and described.

DESCRIPTION

FIG. 1 is a perspective view of a bicycle shifter grip with sharktooth design showing my new design, the broken lines are shown for illustrative purposes only and form no part of the claimed design;

FIG. 2 is a side elevational view thereof; and,

FIG. 3 is an outboard end elevational view thereof, the opposite end being plain and unornamented.
